Here and elsewhere throughout this specification, it will be understood the benzene ring of phenyl can bear any number and kind of substituents such as would occur to the man skilled in organic chemistry. Solely for illustration, and without limitation, such substituents include lower-alkyl, lower-alkoxy, halo (chloro, bromo, iodo, or fluoro), nitro, lower-alkylmercapto, and the like.

The compounds of Formulas Ia, b where R₄ is hydrogen are prepared by reacting an 8-alkyl-10-hydroxy-5-oxo-1,2,3,4-tetrahydro-5H-[1]benzopyrano[3,4-c]pyridine or a 10-alkyl-8-hydroxy-5-oxo-1,2,3,4-tetrahydro-5H-[1]benzopyrano[3,4-c]pyridine, having the respective Formulas IIIa and IIIb, with a lower-alkyl magnesium halide as illustrated by the equation:

where R_1 , R_2 , and R_3 have the meanings given hereinabove, and Hal represents halogen. The reaction is carried out in an organic solvent inert under the conditions of the reaction. Suitable solvents are diethyl ether, dibutyl ether, tetrahydrofuran, anisole, pyridine, and the like. It is preferred to add a solution of the 8-alkyl-10-hydroxy-5-oxo-1,2,3,4-tetrahydro-5H-[1]benzopyrano[3,4-c]pyridine or 10-alkyl-8-hydroxy-5-oxo-1,2,3,4-tetrahydro-5H-[1]benzopyrano[3,4-c]pyridine in a pyridine or anisole solution, or in a mixture of these solvents, to a solution of the Grignard reagent in anisole.

The compounds of Formula IIIa, b in turn are prepared by reacting a 1- R_3 -3-carbo-lower-alkoxy-4-piperidone of Formula IV with a 5-alkylresorcinol of Formula V. The reaction is carried out in a mixture of concentrated sulfuric acid and phosphorus oxychloride or in the presence of other acidic condensation agents such as aluminum chloride, hydrogen chloride, or polyphosphoric acid and is illustrated by the equation:

where R_2 and R_3 are defined as above, and Alk is lower-alkyl.

As indicated by the reaction scheme above, the ring closure of the 1- R_3 -3-carbo-lower-alkoxy-4-piperidone with the 5-alkylresorcinol can take place either by cyclization at the 2-position of the 5-alkylresorcinol, as indicated by the arrow (a), to produce the 8-alkyl-10-hydroxy-5-oxo-1,2,3,4-tetrahydro-5H-[1]benzopyrano[3,4-c]pyridines of Formula IIIa or by cyclization at the 4-position of the 5-alkylresorcinol, as indicated by the arrow (b), to produce the 10-alkyl-8-hydroxy-5-oxo-1,2,3,4-tetrahydro-5H-[1]benzopyrano[3,4-c]pyridines of Formula IIIb. Generally either the compounds of Formula IIIa or of Formula IIIb are produced by either 5-methylresorcinol (R_2 is CH_3) or by 5-(3-methyl-2-octyl)resorcinol (R_2 is $CH_3CH_2CH_2C_6H_{11}$), but in the latter case, the predominant products are the compounds of Formula IIIa owing to the partial steric hindrance of the 4-position of the resorcinol by the rather bulky 3-methyl-2-octyl group in the adjacent 5-position which inhibits cyclization at the 4-position.

The intermediate 5-methyl- and 5-(3-methyl-2-octyl)-resorcinols of Formula V are known in the art.

The intermediate 1- R_3 -3-carbo-lower-alkoxy-4-piperidones of Formula IV are prepared by the method of Prill and McElvain, J. Am. Chem. Soc. 55, 1233 (1933) and of McElvain and Vozza, J. Am. Chem. Soc. 71, 896 (1948).

The compounds of Formulas Ia and Ib where R_3 is hydrogen are also advantageously prepared by catalytically debenzylating, with hydrogen in the presence of a catalyst, the compounds of Formulas Ia, b hereinabove where R_3 is benzyl. The reaction is preferably carried out in an organic solvent inert under the conditions of the reaction, for example methanol, ethanol, isopropanol, and the like. Suitable catalysts are platinum or palladium-on-charcoal. A preferred catalyst is palladium-on-charcoal.

The compounds of Formulas Ia, b or IIa, b, where R_3 is cycloalkyl-lower-alkyl, lower-alkenyl, lower-alkynyl, halo-lower-alkenyl, phenyl-lower-alkyl, phenyl-lower-alkenyl, or phenyl-lower-alkynyl are prepared by reacting the corresponding compounds of Formulas Ia, b or IIa, b, where R_3 is hydrogen with a cycloalkyl-lower-alkyl, lower-alkenyl, lower-alkynyl, halo-lower-alkenyl, phenyl-lower-alkyl, phenyl-lower-alkenyl, or phenyl-lower-alkynyl halide, respectively. The reaction is preferably carried out in an organic solvent inert under the conditions of the reaction, for example methanol, ethanol, isopropanol, or dimethylformamide, and in the presence of an acid-acceptor. The purpose of the acid-acceptor is to take up the hydrogen halide split out during the course of the reaction and is a basic substance which forms water-soluble salts readily separable from the reaction mixture. Suitable acid-acceptors are alkali metal carbonates or bicarbonates, for example sodium or potassium carbonate, or bicarbonate, or alkali metal hydroxides, for example sodium or potassium hydroxide. The reaction can also be carried out in the presence of a molar excess of the bases of Formulas Ia, b or IIa, b where R_3 is hydrogen. A preferred acid-acceptor is sodium carbonate, and a preferred solvent is ethanol.

The compounds of Formulas Ia, b or IIa, b where R_3 is lower-alkanoyl, cycloalkyl-lower-alkanoyl, or phenyl-lower-alkanoyl are prepared by reacting the corresponding compounds of Formulas Ia, b or IIa, b where R_3 is hydrogen with an acid halide or anhydride of a lower-alkanoic, cycloalkyl-lower-alkanoic, or phenyl-lower-alkanoic acid, respectively. The reaction is preferably carried out in an organic solvent inert under the conditions of the reaction, for example benzene, toluene, xylene, and the like, and in the presence of a basic catalyst, for example pyridine, triethylamine, dimethylaniline, and the like. A preferred solvent is benzene, and a preferred basic catalyst is pyridine.

The compounds of Formulas Ia, b or IIa, b where R_3 is cycloalkyl-lower-alkyl and phenyl-lower-alkyl can also be prepared by reducing, with an alkali metal aluminum hydride, the compounds of Formulas Ia, b or IIa, b where R_3 is cycloalkyl-lower-alkanoyl or phenyl-lower-alkanoyl, respectively, and where R_4 is hydrogen or lower-alkyl. The reaction is preferably carried out in an organic solvent inert under the conditions of the reaction, for example diethyl ether, tetrahydrofuran, dibutyl ether, and the like.

The 8-alkyl-10-hydroxy-5,5-di-lower-alkyl-5H-[1]benzopyrano[3,4-c]piperidines and 10-alkyl-8-hydroxy-5,5-di-lower-alkyl-5H-[1]benzopyrano[3,4-c]piperidines of Formulas IIa and IIb, respectively, are prepared by reducing with hydrogen over a suitable catalyst the 8-alkyl-10-hydroxy-5,5-di-lower-alkyl-1,2,3,4-tetrahydro-5H-[1]benzopyrano[3,4-c]pyridines and 10-alkyl-8-hydroxy-5,5-di-lower-alkyl-1,2,3,4-tetrahydro-5H-[1]benzopyrano[3,4-c]pyridines of Formulas Ia and Ib, respectively, where R_1 , R_2 , and R_4 have the meanings given above and R_3 is hydrogen, lower-alkyl, lower-alkanoyl, cycloalkyl-lower-alkyl, cycloalkyl-lower-alkanoyl, phenyl-lower-alkanoyl, or phenyl-lower-alkyl. The reaction is carried out in an organic solvent inert under the conditions of the reaction, for example, methanol, ethanol, isopropanol, and the like. Suitable catalysts include palladium-on-charcoal, platinum, Raney nickel and the like. A preferred catalyst is Raney nickel.

The ester and ether derivatives of the compounds of Formulas Ia, b and IIa, b, that is the compounds where R₄ is lower-alkyl, lower-alkanoyl, carbamyl, N-lower-alkylcarbamyl, N,N-di-lower-alkylcarbamyl, or phosphonyl are prepared by reacting the corresponding compounds where R₄ is hydrogen, preferably in the presence of a basic catalyst, with a lower-alkyl halide, to produce the compound where R₄ is lower-alkyl with a lower-alkanoic anhydride (or mixed anhydride), to produce the compounds where R₄ is lower-alkanoyl; with a molar equivalent of phosgene followed by reaction of the resulting chloroformate with ammonia, a lower-alkylamine, or a di-lower-alkylamine, to produce the compounds where R₄ is, respectively, carbamyl, N-lower-alkylcarbamyl, or N,N-di-lower-alkylcarbamyl; or with one molar equivalent amount of phosphorus oxychloride followed by reaction of the resulting dichlorophosphinate with aqueous sodium or potassium carbonate, to produce the compounds where R₄ is phosphonyl. Suitable solvents are benzene, toluene, xylene, and the like, and suitable basic catalysts are alkali metal carbonates, bicarbonates, or hydroxides, dimethylamine, pyridine, and the like.

The acid-addition salts of the bases herein described are the form in which the bases are most conveniently prepared for use and are the full equivalents of the subject matter specifically claimed. The acid moieties or anions in these salt forms are in themselves neither novel nor critical and therefore can be any acid anion or acid-like substance capable of salt formation with the free base form of the compounds. The preferred type of salts are water-soluble pharmacologically-acceptable salts, that is, salts whose anions are relatively innocuous to the animal organisms in pharmacological doses of the salts, so that the beneficial physiological properties inherent in the free base are not vitiated by side effects ascribable to the anions; in other words, the latter do not substantially affect the pharmacological properties inherent in the cations. In practicing the invention, it has been found convenient to form the hydrochloride salt. However, other appropriate pharmacologically-acceptable salts within the scope of the invention are those derived from mineral acids such as hydrobromic acid, hydroiodic acid, nitric acid, phosphoric acid, sulfamic acid, and sulfuric acid; and organic acids such as acetic acid, citric acid, tartaric acid, lactic acid, methanesulfonic acid, ethanesulfonic acid, quinic acid and the like, giving the hydrobromide, hydroiodide, nitrate, phosphate, sulfamate, sulfate, acetate, citrate, tartrate, lactate, methanesulfonate, ethanesulfonate, and quinate, respectively.

Although pharmacologically-acceptable salts are preferred, those having toxic anions are also useful. All acid-addition salts are useful intermediates as sources of the free base form even if the particular salt per se is not desired as the final product, as for example when the salt is formed only for purposes of purification or identification, or when it is used as an intermediate in preparing a pharmacologically-acceptable salt by ion-exchange procedures.

The compounds of Formulas Ia, b and IIa, b have been shown to possess C.N.S. and cardiovascular activity as evidenced by gross overt changes induced by intravenous administration in mice in standard tests involving observations of psychomotor activity, reactivity to stimuli, and ability to perform normal, non-conditioned motor tasks. This activity indicates their usefulness as psychotropic agents.

The compounds can be prepared for use by dissolving under sterile conditions a salt form of the compounds in water (or an equivalent amount of a non-toxic acid if the free base is used), or in a physiologically compatible aqueous medium such as saline, and stored in ampoules for intramuscular injection. Alternatively, they can be incorporated in unit dosage form as tablets or capsules for oral administration either alone or in combination with suitable adjuvants such as calcium carbonate, starch, lac-

tose, talc, magnesium stearate, gum acacia, and the like. Still further, the compounds can be formulated for oral administration in aqueous alcohol, glycol, or oil solutions or oil-water emulsions in the same manner as conventional medicinal substances are prepared.

The molecular structures of the compounds of our invention were assigned on the basis of study of their infrared, ultraviolet, and NMR spectra and their transformation products, and confirmed by the correspondence between calculated and found values for the elementary analyses for representative examples.

The following examples will further illustrate the invention without, however, limiting it thereto.

EXAMPLE 1

10-hydroxy-8-(3-methyl-2-octyl)-3,5,5-trimethyl-1,2,3,4-tetrahydro-5H-[1]benzopyrano[3,4-c]pyridine

(0.12 mole) of 5-(3-methyl-2-octyl)resorcinol with stirring, and 48 ml. of concentrated sulfuric acid was then added dropwise to the mixture at room temperature. The mixture was then treated with 21 ml. of phosphorus oxychloride, stirred at room temperature for seventy-eight hours, neutralized with aqueous potassium bicarbonate, and the product extracted into chloroform. The organic extracts were washed first with bicarbonate solution and then with water, dried over anhydrous sodium sulfate, and taken to dryness. The crude product (44 g.) was extracted with five 350 ml. portions of boiling acetonitrile, and from the fifth extract there was obtained 7.3 g. of 10 - hydroxy-5-oxo-3-methyl-8-(3-methyl-2-octyl)-1,2,3,4 - tetrahydro - 5H - [1]benzopyrano[3,4-c]pyridine, M.P. 169-173° C.

(B) 10 - hydroxy - 8 - (3 - methyl - 2 - octyl) - 3,5,5-trimethyl - 1, 2,3,4 - tetrahydro - 5H - [1]benzopyrano[3,4-c]pyridine.—A solution of 3.5 g. (0.01 mole) of 10-hydroxy - 5 - oxo - 3 - methyl - 8 - (3 - methyl-2-octyl)-1,2,3,4 - tetrahydro - 5H-[1]benzopyrano[3,4-c]pyridine, dissolved in 65 ml. of pyridine, was added dropwise to a solution of 0.1 mole of methyl magnesium iodide in 100 ml. of anisole. When addition was complete, the mixture was stirred at 30-45° C. for about eight hours, cooled, and the excess Grignard reagent decomposed with 100 ml. of water. The mixture was then acidified with 300 ml. of 4 N sulfuric acid, and steam distilled to remove the anisole. The aqueous residue was then basified by the addition of solid sodium carbonate, and the pyridine removed by steam distillation. The solid which separated from the cooled reaction mixture was collected and dried giving 3.36 g. of the product in free base form. The latter was converted to the hydrochloride salt in ethyl acetate and recrystallized from acetonitrile giving 1.4 g. of 10-hydroxy-8-(3-methyl-2-octyl)-3,5,5-trimethyl-1,2,3,4 - tetrahydro - 5H - [1]benzopyrano[3,4-c]pyridine hydrochloride, M.P. 281-283° C.

Analysis.—Calcd. for C₂₄H₃₇NO₂·HCl (percent): C, 70.65; H, 9.39; N, 3.43. Found (percent): C, 71.07; H, 9.45; N, 3.42.
